JACOB C. BAUER, OF NEW YORK, N. Y.

Design No. 4,174, dated June 28, 1870.

DESIGN FOR A PAPER BOX.

The Schedule referred to in these Letters Patent and making part of the same.

To all whom it may concern:

Be it known that I, JACOB C. BAUER, of the city of New York, in the county and State of New York, have invented a new and original Design for Paper Box; and I do hereby declare that the following is a full, clear, and exact description thereof, which will enable others skilled in the art to make and use the same, reference being had to the accompanying drawing forming part of this specification.

The figure is a perspective view of a paper box, illustrating my improved design.

My invention has for its object to furnish a new and original design for a paper box, intended more particularly for a paper-collar box, but equally applicable for other uses, and which shall be neat and simple, and of such form as to enable it to be easily and elegantly ornamented with bordering and pictures, or to receive the label, or the circular, or business card of the manufacturer; and

It consists in the design hereinafter more fully described and set forth.

The invention relates to that class of paper boxes in which the upper part shuts down over the lower part, that contains the collars or other articles.

The outer edge, A, of the bottom of the lower part,

projects slightly beyond the outer sides of the outer or upper part, B, as shown in the figure, forming a narrow flange, as shown.

The box is made rectangular in its general form, and the upper parts, b', of its ends are made angular, as shown in the figure.

C is the top of the box, which is made angular, as shown in the figure, to fit upon the angular upper edges of the ends b'. The lower edges of the top C project slightly beyond the sides of the part B, in the manner of the eaves of a house. In fact, the general form of the box is that of a small house, and the resemblance may be rendered more perfect by applying the ornamental work in such a way as to represent or suggest doors and windows.

Pictures or other ornaments may be attached to the top, sides, or ends of the part B, or labels, circulars, or cards, as may be desired or convenient.

I claim as my invention—

The design for a paper box herein shown and described.

JACOB C. BAUER.
